US00D870093S

(12) **United States Design Patent** (10) **Patent No.:** **US D870,093 S**
McSweyn (45) **Date of Patent:** **** Dec. 17, 2019**

(54) **DESK ATTACHMENT FOR MAGNETIC DEVICE MOUNT**

6,135,408 A 10/2000 Richter
6,149,116 A 11/2000 Won
6,305,656 B1 10/2001 Wemyss
6,382,482 B1 5/2002 Chao

(71) Applicant: **SCOSCHE INDUSTRIES, INC.**,
Oxnard, CA (US)

(Continued)

(72) Inventor: **Christopher Michael McSweyn**,
Oxnard, CA (US)

FOREIGN PATENT DOCUMENTS

CN	201113495	9/2008
CN	202042680	11/2011

(73) Assignee: **Scosche Industries, Inc.**, Oxnard, CA (US)

(Continued)

(**) Term: **15 Years**

(21) Appl. No.: **29/623,424**

(22) Filed: **Oct. 25, 2017**

(51) **LOC (12) Cl. 03-01**

(52) **U.S. Cl.**

USPC **D14/253**

(74) *Attorney, Agent, or Firm* — Stetina Brunda Garred & Brucker

(57) **CLAIM**

The ornamental design for a desk attachment for magnetic device mount, as shown and described.

DESCRIPTION

FIG. 1 is a front perspective view of a desk attachment for magnetic device mount showing my new design;

FIG. 2 is a rear perspective view thereof;

FIG. 3 is a top plan view thereof;

FIG. 4 is a left side view thereof;

FIG. 5 is a front view thereof;

FIG. 6 is right side view thereof;

FIG. 7 is a rear view thereof; and,

FIG. 8 is a bottom plan view thereof.

The broken lines in the drawings depict environmental subject matter and form no part of the claimed design.

1 Claim, 3 Drawing Sheets
